PROCESS FOR THE SOLVENT EXTRACTION
OF LUBRICATING OILSDavid R. Merrill, Long Beach, Calif., assignor to
Union Oil Company of California, Los Angeles,
Calif., a corporation of California

Application December 5, 1933, Serial No. 701,016

9 Claims. (Cl. 196—13)

This invention relates to a process for the treatment of petroleum with selective solvents.

In the production of lubricating oil from crude petroleum residues or distillates, it is becoming conventional in the art to separate the desirable paraffinic hydrocarbons from the undesirable olefinic, naphthenic and/or aromatic compounds by the use of solvents which selectively dissolve the undesirable hydrocarbons but which exhibit only a very limited solvent power for the desirable paraffinic hydrocarbons.

When I use the term "paraffinic hydrocarbons" I mean those relatively highly saturated compounds which are present in petroleum characterized by a low temperature viscosity susceptibility, i. e., they exhibit a minimum change in viscosity for a given change in temperature, and characterized by relative stability to air and sunlight, exhibiting little tendency toward discoloration or sludge formation. This definition is not meant to include those compounds which are usually solid or semi-solid at ordinary temperatures and which are known as "wax" or "petrolatum". As a matter of convenience hereafter, I will refer to the undesirable components, such as olefinic, naphthenic and/or aromatic hydrocarbons as the "non-paraffinic" components of petroleum. These latter fractions are characterized by a relatively high temperature viscosity susceptibility and are not stable to air and sunlight, exhibiting discoloration and sludge formation.

A further indication of the purity of a lubricating oil is its viscosity gravity constant. This constant represents the paraffinity or naphthenicity of an oil. A high value represents a high degree of naphthenicity while low values indicate relatively greater paraffinity. Lubricating oils from natural crudes range from around 0.903 viscosity gravity constant for an extreme Gulf Coast type to 0.807 for an extreme Pennsylvania type, or even beyond. The viscosity gravity constant referred to in this application has been determined by the method employed by Hill and Coates as set forth in the Journal of Industrial and Engineering Chemistry, vol. 20, page 641 of 1928.

A number of selective solvents for this purpose have been found; for example, it has been shown that such materials as liquid sulphur dioxide, beta beta dichlorethyl ether, chloraniline, nitrobenzene, aniline and furfural are highly selective as solvents for the non-paraffinic hydrocarbons. These solvents may be used alone or modified by the presence of such agents as carbon bisulphide,

xylene, benzene, toluene, carbon tetrachloride, ethers, tetrachlor-ethane or the like. When these relatively heavy solvents are commingled with petroleum or petroleum fractions under the proper conditions of temperature, the undesirable non-paraffinic hydrocarbons pass into solution to a greater or less extent but the desirable paraffinic hydrocarbons remain largely undissolved. The solution of undesirable hydrocarbons and solvent settles to the bottom of the container and forms what is known as an extract phase. The relatively light paraffinic hydrocarbons rise to the top of the vessel and form a raffinate phase. These phases are then readily separable by ordinary decantation means. The raffinate phase is usually found to contain a small quantity of the selective solvent and the extract phase ordinarily contains a relatively large quantity of the solvent. These fractions may be purified by distillation whereby the solvent is distilled away from the hydrocarbon oils.

Due to the general similarity of the various hydrocarbon components of mineral oil fractions such as lubricating oils, solubilities of the undesirable, non-paraffinic fractions and of the desirable paraffinic fractions in a selective solvent usually differ only in degree and there is, therefore, a tendency for desirable, high grade paraffinic oil to be carried away with the extract resulting in a loss in the yield of paraffinic fractions obtained. In other words, in a phase separation of extract and raffinate fractions from mineral oil employing a selective solvent, an equilibrium of paraffinic components as well as non-paraffinic components is established between the phases. Consequently, some of the desirable paraffinic fraction is found in the extract instead of in the raffinate.

It is an object of my invention to reduce the loss of these valuable components in the extract phase.

In producing a high quality final raffinate from a stock containing a limited quantity of such raffinate, it is necessary to dissolve and carry away a large proportion of the original feed. In the case of many solvents, such as dichlorethyl ether, and to an even greater extent liquid sulphur dioxide alone or modified with benzene, the solubility of the oil in the extract phase even at temperatures within 5° F. or 10° F. of the miscibility temperature is rather limited. In consequence, it is necessary in refining such stocks for the production of low viscosity gravity constant oils to use a large proportion of solvent to feed stock in order to remove in solution from

the system the undesirable constituents of the feed.

For successful operation it is necessary that the conditions of extraction should be such that complete miscibility of the oil with the solvent does not occur, for if complete miscibility takes place it is obvious that no raffinate can be produced. The higher the temperature of complete miscibility, the higher is the temperature at which separation can take place and the better is the quality of the raffinate thus obtained. The temperature of complete miscibility of all the oil with the solvent in any stage of extraction is a function of both the average composition of the oil in that stage, including the oil in both phases, and the proportion of total solvent to total oil in that stage.

In operation on an oil containing a substantial proportion of oils of highly aromatic or non-paraffinic character and very high viscosity gravity constant, difficulty has been encountered from miscibility in attempting to operate the feed stage at the desired high temperature. For instance, with dichlorethyl ether, miscibility was encountered in attempting to operate the feed stage at 120° F. and it has been found necessary to lower this temperature to about 80 to 85° F. in order to avoid complete miscibility at this point and thus permit practical operation. While using such comparatively low temperatures at the feed stage, it is evident that the extraction at this point is reduced and it has been found necessary to employ somewhat larger proportions of solvent to produce a final raffinate of the desired quality. It is therefore desirable to treat such highly aromatic oils, for instance, Kettleman Hills deasphaltized and dewaxed long residuum having a viscosity gravity constant of 0.87, by a pre-extraction to remove the highly aromatic oils to a greater or less extent before proceeding with the extraction to separate the oils of very low viscosity gravity constant from those characterized by intermediate viscosity gravity constant.

While it is evident that such a pre-extraction can be accomplished as an entirely separate operation with solvent of either the same or a different type from that employed in the subsequent extraction, the additional solvent requirements increase the expense of operation.

It is another object of my invention to accomplish said pre-extraction without the use of additional quantities of solvent.

The drawing is a diagrammatic view of a preferred apparatus for carrying out my invention. Referring to the figure, feed stock enters the system via line 10 controlled by valve 11 by action of pump 12 and is intermixed with a solvent issuing from line 14. The combined stream of oil and solvent passes through orifice mixer 15 and line 16 into separator 17. Raffinate phase from separator 17 exits via line 18 controlled by valve 19 by action of pump 20 and passes with extract phase from extractor 100, to be described, through orifice mixer 21 and line 22 into a section 65 of extraction column 25. In this column the oil passes countercurrently with a selective solvent brought from tank 26 via line 27 controlled by valve 28 by action of pump 29, via line 30 controlled by valve 31, through orifice mixer 32 and 70 via line 33. High grade raffinate is removed from column 25 through line 35 controlled by valve 36. Extract phase is removed from column 25 through line 37 controlled by valve 38 by action of pump 39. Column 25 comprises sections 40 to 47 separated by imperforate plates 50. Each section

comprises a mixing zone 51 and a settling zone 52 separated by plate 53 provided with port 54. Separator 17, described above, is likewise divided into similar zones.

Connected with sections 41 to 46 are lines 55 with valves 56 and pumps 57 to remove the extract phases from these sections and lines 58 with valves 59 and pumps 60 are provided to remove the raffinate phases therefrom. The extract phases from upper sections are commingled in lines 61 with the raffinate phases from lower sections and the mixtures are passed through orifice mixers 62 and lines 63 into the respective intermediate sections. The raffinate phase from section 46 is removed therefrom by action of pump 67 through line 65 controlled by valve 66 and is intermixed in line 30 with fresh solvent entering column 25.

In the above-described apparatus, solvent is introduced into the upper section of extractor 25, for example section 47 and the oil is introduced into a lower or tertiary section, for instance section 45. Extraction takes place in all sections and the extract phase from the upper section is commingled in the intermediate or secondary section, for example, section 46 with the raffinate produced in the lower section. Raffinate from the intermediate section travels to the upper section and extract from the intermediate section passes to the lower section.

Because of the magnitude of the partition coefficient of paraffinic constituents between the raffinate and extract phases in any one section, the presence of the highly paraffinic raffinate results in substantial proportions of the paraffinic components passing into the extract phase. By intermixing the less paraffinic raffinate, for instance from section 45 with the extract phase from section 47 containing a relatively high proportion of paraffinic materials and causing a phase separation as in section 46, at least a portion of the paraffinic fractions will pass from the extract into the raffinate.

By contacting an extract-solvent mixture from an upper section of the tower with a raffinate from a lower section, a redistribution of paraffinic fractions takes place. The extract-solvent mixture contains so large a proportion of paraffinic hydrocarbons and the raffinate from a lower section contains relatively so small a proportion of these hydrocarbons that when said extract and said raffinate are mingled in the presence of the solvent, sufficient paraffinic fractions pass from the extract to the raffinate to establish equilibrium between the two phases. Also, at the same time, some of the non-paraffinic fractions pass from the raffinate to the extract, resulting in a more paraffinic raffinate and a less paraffinic extract. Consequently, after a succession of such steps, the final extract contains the least amount of paraffin fractions and the final raffinate contains those paraffinic fractions which are normally lost in the extract. The solvent associated with the extract and raffinate can be removed therefrom by usual means such as by distillation.

Extract phase issuing from column 25 through line 37 is passed through cooler 70 where its temperature is reduced sufficiently to cause phase separation in separator 71 to which it passes through line 72. Rejected raffinate phase insoluble under the conditions existing in separator 71 is passed through line 73 controlled by valve 74 by action of pump 75 into contact with extract phase from section 41 and thence is intro-

duced into rectification section 40 via line 61, orifice mixer 62 and line 63. Extract phase in separator 71 is removed therefrom by action of pump 78 via line 76 controlled by valve 77. This raffinate passing through the rectification stage becomes enriched in high grade components and loss of these valuable fractions in the extract phase is thus reduced.

Returning to the first stage of extraction in separator 17, the extract phase is removed therefrom via line 80, valve 81 and pump 82 and thence passes through cooler 83 where its temperature is sufficiently reduced to cause a rejection of oil in separator 85 to which the stream passes through line 84. Low grade extract is removed from separator 85 through line 86 controlled by valve 87. The rejected oil from 85 may contain a substantial proportion of paraffinic oil and may be forced by pump 88 through lines 89 and 90 and valve 91 into intermixture with the primary raffinate from separator 17 which passes through line 18 on its way to section 41 of column 25.

If desired, the rejected oil from separator 85 may pass through line 89 and valve 92 into contact with the extract phase produced in separator 71 passing through line 76. This mixture then travels through orifice mixer 95 and line 96 into extractor 100 in which it is counter-currently extracted with a selective solvent from tank 26 passing through lines 27 and 30, valve 101, orifice mixer 102 and line 103. An intermediate grade raffinate is removed from extractor 100 via line 104 controlled by valve 105. Extract phase travels from extractor 100 by action of pump 106 through line 107 controlled by valve 108 and passes through cooler 109 wherein its temperature is reduced sufficiently to cause phase separation in separator 110 to which it passes through line 111. Rejected oil is removed by pump 112 through line 113 and valve 114 and is returned into column 100 for rectification in a manner similar to the rectification of the rejected oil from separator 71 in rectification zone 40 of column 25. Extract phase comprising contaminated solvent from separator 110 passes through line 14, valve 115 and pump 116 into admixture with oil feed passing through line 10 for extraction in the manner above described. Preferably, temperature conditions in separator 110 will be such that the extract phase removed via line 14 will comprise solvent contaminated with 3% or less oil.

Extractor 100, like column 25, is divided into a number of sections 120, 121 and 122, comprising mixing zones 51, settling zones 52 and plates 53 provided with ports 54. Extract phase from section 122 is intermixed with raffinate phase from section 120 and the mixture is passed into the intermediate section 121 in a manner similar to the flow of material in column 25. Raffinate phase from section 121 passes into section 122 together with fresh solvent by flow through line 123, valve 124, pump 125, line 30, orifice mixer 102 and line 103. Extract phase in section 121 is forced by action of pump 126 in line 127 through valve 128 and line 129 into contact with the above described mixture flowing through line 76. Or, if desired, the extract phase may travel from section 121 through line 127 and valve 130 into admixture with the above described oil passing through line 18 from separator 17.

As an example of the operation of this apparatus, the above-described Kettleman Hills deasphaltized and dewaxed long residuum characterized by a viscosity gravity constant of about

0.87 was extracted with a selective solvent comprising 75% liquid sulphur dioxide and 25% benzene. The oil feed was extracted in the first stage in separator 17 at 40° F. The extract phase from separator 17 was cooled to 20° F. so that a rejected oil was removed in separator 85. The temperature in column 25 was progressively increased from 95° F. in section 40 to 130° F. in section 41 into which the oil was introduced from separator 17 was maintained at 105° F. This temperature is appreciably below the miscibility temperature after said pre-extraction has removed a substantial portion of the highly aromatic fractions.

Extract phase from column 25 was cooled to 80° F. in cooler 10 to cause phase separation in separator 71. The temperature in extractor 100 was progressively increased from 60° F. in section 120 to 80° F. in section 122. The extract phase from extractor 100 was cooled to 20° F. in cooler 109 in order to cause rejection of a raffinate in separator 110. About 250 volume percent. of solvent to oil introduced into the system was employed in column 25 and an additional amount of solvent to the extent of 40 volume percent. was introduced into extractor 100. The contaminated solvent from separator 110 was used as the selective solvent for the primary extraction in separator 17.

In my invention above described, the valuable paraffinic components normally lost in the extract phase are recovered in the raffinate phases and the pre-extraction in separator 17 is accomplished by a recovered solvent from another stage of the extraction system. It is to be understood that the stages shown may be either entirely separate stages or merely regions of a continuous extractor in which different temperatures are maintained. Also, the temperatures set forth are merely by way of illustration and may be varied for other stocks and solvents. Furthermore, the number of stages shown in the figures is to be considered merely typical for these general conditions and may be varied as desired. Thus, more rectification stages may be employed and the number of extraction stages may be increased or decreased as is found desirable in any particular circumstance.

My invention is capable of many modifications and variations as will be apparent to those skilled in the art within the scope of the following claims.

I claim:

1. A process for the separation of paraffinic and non-paraffinic fractions from mineral oil containing the same which comprises extracting said oil with a selective solvent, separating insoluble raffinate from the extract phase, cooling said extract phase to separate a rejected oil therefrom, extracting said rejected oil with a selective solvent, cooling the extract phase from said last mentioned extraction to separate a rejected oil therefrom, returning the last mentioned rejected oil to said last mentioned extraction to rectify the same and returning extract phase from said last mentioned cooling to said first mentioned extraction to operate as a selective solvent therein.

2. A process for the separation of paraffinic and non-paraffinic fractions from mineral oil containing the same which comprises extracting said oil with a selective solvent to separate an insoluble raffinate from the extract phase, cooling said extract phase to separate a rejected oil therefrom, extracting said rejected oil with a selective solvent, cooling the extract phase from said last

- mentioned extraction to separate a rejected oil from contaminated solvent, returning said contaminated solvent to said first mentioned extraction to operate as a selective solvent therein and further extracting the raffinate from said first mentioned extraction with selective solvent to produce a high quality raffinate and an intermediate grade extract therefrom.
3. A process for the separation of paraffinic and non-paraffinic fractions from mineral oil containing the same which comprises extracting said oil with a selective solvent to separate an insoluble raffinate from the extract phase, subjecting said raffinate to a second extraction with a selective solvent to produce a high quality raffinate and an intermediate grade extract therefrom, cooling said intermediate grade extract to separate a rejected oil from contaminated solvent, cooling the extract phase from said first mentioned extraction to separate a rejected oil therefrom and extracting said last mentioned rejected oil with said contaminated solvent.
4. A process for the separation of paraffinic and non-paraffinic fractions from mineral oil containing the same which comprises extracting said oil with a selective solvent to separate an insoluble raffinate from the extract phase, subjecting said raffinate to a second extraction with a selective solvent to produce a high quality raffinate and an intermediate grade extract therefrom, cooling said intermediate grade extract to separate a rejected oil from contaminated solvent, cooling the extract phase from said first mentioned extraction to separate a rejected oil therefrom, extracting said last mentioned rejected oil with said contaminated solvent, cooling the extract phase from said last mentioned extraction to separate a rejected oil from contaminated solvent and returning said last mentioned contaminated solvent to said first mentioned extraction to operate as a selective solvent therein.
5. A process for the separation of paraffinic and non-paraffinic fractions from mineral oil containing the same which comprises extracting said oil with a selective solvent to separate an insoluble raffinate from the extract phase, subjecting said raffinate to a second extraction with a selective solvent to produce a high quality raffinate and an intermediate grade extract therefrom, cooling said intermediate grade extract to separate a rejected oil from contaminated solvent, returning said rejected oil to said second extraction to rectify the same, cooling the extract phase from said first mentioned extraction

tion to separate a rejected oil therefrom and extracting said last mentioned rejected oil with said contaminated solvent.

6. A process for the separation of paraffinic and non-paraffinic fractions from mineral oil containing the same which comprises extracting said oil with a selective solvent to separate an insoluble raffinate from the extract phase, cooling said extract phase to separate a rejected oil therefrom, mixing said last mentioned rejected oil with said first mentioned raffinate and extracting said mixture with a selective solvent to produce a high grade raffinate and an extract phase.

7. A process for the separation of paraffinic and non-paraffinic fractions from mineral oil containing the same which comprises extracting said oil with a selective solvent to separate an insoluble raffinate from the extract phase, cooling said extract phase to separate a rejected oil therefrom, mixing said last mentioned rejected oil with said first mentioned raffinate, extracting said mixture with a selective solvent to produce a high grade raffinate and an intermediate extract phase and returning said intermediate extract phase to said first mentioned extraction to operate as a solvent therein.

8. A process for the separation of oil into fractions with a selective solvent which comprises commingling said oil with a selective solvent and thereby producing an extract phase and a raffinate phase, separating said phases, passing said raffinate phase to a second extraction stage and commingling said raffinate phase passed to said second extraction stage with a selective solvent, thereby producing a final raffinate phase and a second extract phase, separating said phases, cooling said second extract phase and thereby causing a portion of the relatively more paraffinic oil present in said second extract phase to be forced out of solution, separating the oils forced out of solution by cooling said second extract phase from the remaining oils dissolved in said second extract phase and returning said oils forced out of solution by cooling said second extract phase to said second extraction stage.

9. A process as claimed in claim 8 in which the oil recovered from the second extract phase by cooling is returned to the second extraction stage at a point intermediate the point of introduction of oil into said second extraction stage and removal of second extract phase from said second extraction stage.
